(57) **CLAIM**

I claim the ornamental design for a height-adjustable toilet safety frame, as shown and described.

DESCRIPTION

FIG. 1 is a perspective view of a height-adjustable toilet safety frame, showing our new design in a raised configuration;

FIG. 2 is a front elevational view of FIG. 1;

FIG. 3 is a rear elevational view of FIG. 1;

FIG. 4 is a left-side elevational view of FIG. 1, the right-side elevational view being a mirror image thereof;

FIG. 5 is a top plan view of FIG. 1;

FIG. 6 is a bottom plan view of FIG. 1;

FIG. 7 is a perspective view thereof, illustrated in a lowered configuration;

FIG. 8 is a rear elevational view of FIG. 7; and,

FIG. 9 is a left-side elevational view of FIG. 7, the right-side elevational view being a mirror image thereof.

1 Claim, 9 Drawing Sheets
